NELSON I. CAMPBELL AND ABRAHAM MARTIN HERBSMAN, OF LOS ANGELES,
CALIFORNIA.

MARKING GUIDE.

Application filed September 5, 1923. Serial No. 661,033.

To all whom it may concern:

Be it known that we, NELSON I. CAMPBELL and ABRAHAM MARTIN HERBSMAN, citizens of the United States, residing at Los Angeles, in the county of Los Angeles and State of California, have invented new and useful Improvements in Marking Guides, of which the following is a specification.

Our invention relates to marking guides and consists of the novel features herein shown, described and claimed.

The leading object is to make a marking guide for use upon round objects such as pipe for marking the object to be cut at an angle, the cutting to be done with a hack saw, cutting torch, or the like, as in making right angled elbows and other angular constructions.

Other objects and advantages will appear from the drawings and specification.

The drawings illustrate a marking guide embodying the principles of our invention and illustrate its use.

Fig. 1 is a view of the marking guide unrolled upon a flat surface.

Fig. 2 is a plan view of the marking guide applied to a pipe.

Fig. 3 is an elevation of the view in Fig. 2.

Fig. 4 is a plan view of a completed joint made by cutting a pipe on the angle formed by the marking guide illustrated in Figs. 1 to 3.

Fig. 5 illustrates a modification of the invention in which marking guide openings are provided for marking on a pipe the line of intersection therewith of any one of several planes meeting the pipe at different angles.

The details and operation shown in the drawings are as follows:

The rectangular plate 15 is preferably formed of transparent material such as celluloid and is flexible so that it may be easily wound around the object to be marked.

The two opposite end edges 16 are a sufficient distance apart to allow the plate 15 to reach around the object to be marked. The edges 16 are reinforced by straps 17. The two side edges of the plate 15 are reinforced by straps 18 secured thereto and provided at corresponding ends with buckles 19 and at opposite ends with free tongues 20 adapted to engage the buckles. Preferably, each marking guide is constructed to fit pipe

or the like of a certain diameter. The line 55 of intersection which it is desired to mark upon a pipe is laid out in development upon the flat surface of the stencil 15 and narrow slots or perforations 21 cut upon this line, as shown in Fig. 1.

In application of the marking guide, it is rolled about a pipe 22, as shown in Fig. 2, and the tongues 20 of straps 18 secured in buckles 19, the operator being careful in adjusting the marking guide before tightening the straps 18 so that the abutting edges 16 are parallel with the axis of the pipe 22. The marking guide is used mainly for marking pipe to be cut for making joints by rotating one of the divided ends 70 of the pipe 22, as section 23, 180 degrees about its axis and welding it to the other section of pipe 22, as shown in Fig. 4. It is therefore necessary that the marking guide be so turned about the axis of pipe 22 75 that the plane determined by perforations 21 shall be perpendicular to the plane in which the angle of the joint in the pipe 22 is desired to lie.

The marking guide 15 being secured to 80 the pipe 22, as shown in Fig. 2, in proper adjustment, paint is applied to pipe 22 through perforations 21 and the marking guide is then removed.

While it is thought to be easier to make 85 the mark with a suitable paint, it is obvious that the mark may be scratched with a tool such as a prick punch, chisel, or scratcher, or with a slate pencil, chalk or soapstone, the only requirement being that the mark 90 shall be definite and easily followed in cutting the pipe. Large pipe is preferably cut with a cutting torch and the mark should be such as will remain as long as possible under the action of the torch.

It can thus be seen that we have provided a very simple, durable and inexpensive marking guide which is accurately and easily operated. In case it may be desired to use one marking guide for delineating the 100 intersection of a plane with a pipe at different angles, perforations may be provided in the marking guide, as shown in Fig. 5, in development of the various lines of intersection it is desired to delineate.

The principal use is in marking pipe to be cut at angles of 45° and 30° and 20° and at any desired point between these angles.

The intention is that in shops where a large amount of pipe cutting is to be done, the marking guides will be made and laid out especially for the pipe to be handled and the angles to be cut.

While we prefer to use transparent celluloid so that the operator can see through the celluloid to locate the mark properly upon the pipe, it is not necessary that the sheet be 10 transparent. Other means of locating the starting point of the mark might be devised.

What we claim is:

1. A marking guide comprising a sheet 15 adapted to be wrapped around a pipe and having perforations laid out so that the pipe

may be marked through the perforations for making a cut at the desired angle.

2. A marking guide comprising a sheet, and flexible straps at the edge of the sheet 20 having buckles thereon, said sheet being adapted to be wrapped around a pipe and clamped thereto by the straps and buckles, and having perforations laid out through the sheet so that the pipe may be marked 25 through the perforations for making a cut at the desired angle.

In testimony whereof we have signed our names to this specification.

NELSON I. CAMPBELL.
A. M. HERBSMAN.
